UNITED STATES PATENT OFFICE.

COLIN CAMPBELL CALDER AND ROBERT GEORGE EUSTACE, OF LONDON,
ENGLAND.

CLIP.

No. 807,151.

Specification of Letters Patent.

Patented Dec. 12, 1905.

Application filed June 21, 1905. Serial No. 266,200.

To all whom it may concern:

Be it known that we, COLIN CAMPBELL CALDER and ROBERT GEORGE EUSTACE, subjects of the King of Great Britain, residing at London, England, have invented an Improved Necktie or the Like Clip or Fastener, of which the following is a specification.

This invention relates to an improved necktie or like clip or fastener, and has for its object to provide a cheap and efficient clip or fastener that will hold a necktie firmly to a shirt-front without injury to the tie or the shirt.

The said invention provides a clip or fastener that will lie substantially flat and not press uncomfortably against the chest nor cause the wearer's outer clothing to bulge in an ungainly manner, such as usually accompanies the wearing of the clips or fasteners heretofore in use.

The improved clip or fastener is illustrated in the accompanying drawings, in which—

Figure 1 is a front view, and Fig. 2 is a side view, thereof.

The improved clip is made of metallic wire or other suitable material possessing sufficient strength and resiliency. A piece of such wire of the required length is bent into two loops *a a*, as shown in the drawings.

The wire on both sides of the looped portion is then bent downward and inward until the ends or limbs *b b* cross at an angle of about forty-five degrees, the loops and limbs being arranged to lie substantially in the same plane.

The material is initially strained, so that these limbs bear against each other with an appreciable force.

The limbs *b b* at the parts *c c* beyond the crossing are oppositely curved to form arcs the planes of which are at right angles, or thereabout, to the mean plane of the clip as a whole, as shown in the drawings. Said parts *c c* cross each other at *d*. The bending of the ends in this manner provides jaws or inclines facilitating the insertion of the tie and shirt-front between the limbs of the clip and insuring a more secure grip of the clip or fastener upon such materials as may be inserted therein.

What we claim is—

A fastener or clip consisting of a piece of wire bent to form a looped portion, limbs extending from said looped portion, crossing each other, and lying in substantially the same plane as the looped portion, the portions of said limbs beyond the crossing relatively to the looped portion lying in a plane substantially at right angles to said first-named plane and being also crossed, substantially as described.

In testimony whereof we have hereunto set our hands in presence of two subscribing witnesses.

COLIN CAMPBELL CALDER.
ROBERT GEORGE EUSTACE.
